UNITED STATES PATENT OFFICE.

WILLIAM W. DEAN, OF ELYRIA, OHIO; CURTIS B. CAMP, TRUSTEE, APPOINTED BY COURT.

PROTECTIVE DEVICE.

1,125,491.

Specification of Letters Patent.

Patented Jan. 19, 1915.

Application filed May 19, 1905. Serial No. 261,123.

To all whom it may concern:

Be it known that I, WILLIAM W. DEAN, a citizen of the United States, residing at Elyria, in the county of Lorain and State of Ohio, have invented certain new and useful Improvements in Protective Devices, of which the following is a specification, reference being had therein to the accompanying drawing.

- 10 My invention relates to protective devices for electrical apparatus and circuits, and particularly to sneak current arresters, or so-called "heat coils" as used in telephone systems. Such devices are commonly employed in telephone exchanges, for the purpose of protecting the outside lines, or the inside apparatus connected therewith, from the effects of such currents as would fail to be excluded by high potential arresters 15 or spark gaps. Ordinarily, one of the so-called heat coils is included in each side of each line, and all these devices are mounted together on a convenient frame or rack with terminals such as to afford easy means of 20 connection, and for testing. In mounting the devices, the frame or rack commonly has on each strip rows of contact springs in and between which the individual heat coils are mounted, there being one group in the 25 row for each line there represented, and two heat coils, one for each side of the line. Such an arrangement is shown in the patent to Williams, No. 588,206, granted Aug. 17, 1897. A ground strip is provided, which is 30 sometimes connected to the frame itself, and when a coil becomes hot owing to excessive current, it heats up and melts a body of solder and thereby releases a normally held contact spring to connect with the ground 35 strip and at the same time break with a mate spring. This grounds the line side, and leaves the switch-board circuit with its protected apparatus entirely cut off. The heat-coil itself comprises three elements, the 40 circuit parts, the winding or heating device, and the solder or cement acted upon by the heat from the coil. The winding is sometimes replaced by a body of carbon or the like, the coil however being most customary. 45 My invention has for its object to simplify and cheapen the protective outfits now in use, and at the same time increase the efficiency of the apparatus. Instead of using a coil for each side of the line, I propose to use 50 a single device for both sides of the line,

which may comprise an aggregation of either coils or other agencies for developing heat or for otherwise controlling the line circuit.

In its simplest form my invention comprises a coil composed of two windings differentially laid upon a spool arranged in proximity to a soldered surface by which is supported a spring or pair of springs controlling the line and switch-board circuits. 60 The line is led in and one side goes through each of the differential windings. Voice currents are thus unaffected, since they neutralize each other in the coils. Sneak currents, however, produce a double effect, since 65 both coils act upon a single mass of solder.

The economy and simplicity of my device will be seen at a glance without explanation, only one coil being required per line instead of two.

75 In view of the many well known arrangements of contact springs, ground strips and the like, it is unnecessary for me to set forth in detail the various connections that may be made with my invention, and I wish it 80 understood that the invention is independent thereof in its essential principle, being usable with any system.

Instead of coils I also contemplate providing two pieces of carbon, or the like, for 85 heating means, in proximity to the same solder or other circuit controlling device.

My invention is illustrated in the accompanying drawing, wherein—

Figure 1 shows a heat coil embodying the 90 invention, and coöperating parts and connections; Fig. 2 is a modification of the heat coil; Fig. 3 is a modification of the entire device; and Fig. 4 is held detail view of the plug and detaining plate.

95 In the drawings, Fig. 1, A is a heat coil, supported in any suitable manner, comprising the spool, a (which may be of copper), with two differential windings, a' and a''. This coil has a plug of metal, B, having a 100 flat head, b, the stem of the plug lying within the spool in a position to be heated by means of the windings. The plug is of a metal such as copper, which will conduct heat rapidly, and the head, b, therefore receives the generated heat from the stem. Upon this head is soldered one end of a 105 detaining strip, D, of metal, having bushed openings, d and d', receiving the ends of the line springs, e and e', of the line set, E, 110

corresponding to the set shown in Fig. 1 of the Williams patent referred to. Each spring has a normally open ground contact, g or g' , and each may have a normally closed contact connected to the switchboard circuit 5-6; but in the simpler form shown the line is not opened but merely grounded for sneak currents. Circuit is traced from line wire 1 to spring, e , wire 3, winding a^2 , 10 wire 5, the switchboard apparatus, wire 6, winding a' , wire 4, spring e' , wire 2 and out. The operation is of course obvious without description. When the coil heats the solder, C, melts (or the equivalent cement softens). 15 The springs, e , e' , drop to ground contacts. In the form shown in Fig. 2, I have provided the coil with heads, so that it may be supported by springs adapted to move longitudinally of the coil when the solder or 20 cement softens. In the modification shown in Fig. 3, I have shown the line set E of contact springs mounted upon an iron base x which is connected to ground. The contact springs e and e' are mounted on and 25 insulated from the base by insulating strips, F, held to the base by screws f . An arm, G extends horizontally from where it is secured to the base by the screws, f , over the contact springs e and e' , to a point approximately 30 midway the length of the springs e and e' where it is bent upward to form a support for the spool a of the heat coil A. This coil is constructed substantially the 35 same as that shown in Fig. 1 and is provided with a headed copper plug B, which is different from that shown in Fig. 1 in that it is provided with a button B^3 adapted to engage a slot d^2 formed in the detaining strip D. The strip D shown in this figure is provided 40 with a bushed opening d^3 at each end, and the plug B is adapted to turn in the spool a.

When the device is in operative position as shown in Fig. 3, the spring e' has its 45 hooked end e^5 engaging the lower bushed opening d^3 and the lower end of the slot d^2 is in contact with the button B^3 . The detaining strip is soldered to the head b of the plug B and preferably also to the button B^3 . 50 The spring e is normally held from contact with the ground plate and the spring e' normally pulls downward on the detaining plate D. When the coil heats and the solder melts the contact spring e' pulls the plate 55 down so as to allow it to engage a raised contact e^2 and to force the spring e into engagement with a contact e^3 , thus grounding both sides of the line. As the coils cool, the detaining plate becomes resoldered in this 60 depressed position. It is then only necessary to remove the plug and reverse it, when the device is again in operative condition.

I wish it distinctly understood that I am not confined to the specific embodiment of 65 my invention herein disclosed, but that the

same may be varied in many ways without departing from the spirit of the invention.

Having thus described my invention what I claim and desire to secure by Letters Patent is:

1. In a protective device for electrical systems, the combination with a line circuit, of a controlling switch therefor, means adapted to respond to an electric current connected in different portions of said line circuit and separately or jointly acting to operate said switch and means for grounding the switch when operated. 75

2. In a protective device for electrical systems, the combination with a line circuit, of a controlling switch therefor, a plurality of heating devices to jointly or separately operate said switch, and a ground plate contacting with said switch when the switch is operated. 80

3. In a protective device for electrical systems, the combination with a line circuit, of a controlling switch therefor, a plurality of heat coils connected in different portions of said circuit to jointly or separately act upon said switch to operate the same, and means for grounding the switch. 90

4. In a protective device for electrical systems, the combination of a thermally operable switch, said switch having a ground contact, and plurality of current controlled devices to jointly or separately act to put the switch on the ground contact. 95

5. In a protective system, the combination with a line circuit, a plurality of current responsive devices included in series in different portions of the line, a ground contact, a switch connected to line, and means acting on the joint or separate operation of said devices to permit said switch to engage with the ground contact. 105

6. In a protective device for electrical systems, the combination with a switch, of thermally operable securing means therefor, a plurality of current controlled devices, and means whereby such devices are adapted to act singly or jointly to release said securing means. 110

7. In a protective device for electrical systems, the combination with a switch, of thermally operable securing means therefor, and a plurality of current controlled devices adapted to act singly or jointly to release said securing means, said means having provision for automatically resecuring itself in condition adapted for another operation when such switch is manually readjusted. 120

8. In an electrical system, a circuit to be protected, and controlling means for said circuit comprising contacts connected thereto, a mechanical support for said contacts, a holding device for the contacts secured 125

on the support by fusible material, and a pair of heating elements mounted in proximity to said fusible material and connected in opposite sides of the circuit, substantially as described.

9. In an electrical system, a circuit to be protected, a protective device comprising controlling contacts, and a self-soldering heat cartridge mounted on the support and controlling the contacts, said cartridge having two windings and said windings being connected in different parts of the circuit to be protected, whereby sneak currents in either one or both of said different parts of the circuit will actuate the protective device, substantially as described.
10. In an electrical system, a circuit to be protected, controlling contacts for said circuit, a mechanical support for said contacts, and a self-soldering heat cartridge controlling said contacts, said cartridge having two windings and said windings being

connected in opposite sides of the circuit to be protected, substantially as described.

11. In an electrical system, a circuit to be protected and a protective device constituting a single current controlled element, with means to control both sides of the circuit, and a plurality of actuating means therefor connected and responsive to current in both sides of the circuit, substantially as described.

12. In an electrical system, a line circuit, a controlling switch therefor, means for controlling said switch, a plurality of current carrying means controlling said first means, and a grounded plate associated with said switch.

In testimony whereof I have affixed my signature in presence of two witnesses.

WILLIAM W. DEAN.
